COMBINATION SIGHT AND INDICATOR FOR
TRAFFIC CONTROL PROJECTORS

Wilbur T. Harding, Dayton, Ohio

Application January 7, 1936, Serial No. 57,926

7 Claims. (Cl. 177—329)

(Granted under the act of March 3, 1883, as
amended April 30, 1928; 370 O. G. 757)

The invention described herein may be manufactured and used by or for the Government for governmental purposes, without the payment to me of any royalty thereon.

5 This invention relates to improvements in traffic control devices of the type projecting signal light beams of different colors and the objects of the improvements are:

First, to provide an air traffic control device 10 designed for use either during the day or night in transmitting to a selected airplane such visual signals as are necessary to direct traffic into and out of an airdrome; second, to provide an air traffic control device designed for ground use and 15 including a signal projector having two handle assemblies for directing the beam and controlling the signal; third, to provide an air traffic control signal projector having a sighting arrangement which gives a positive check of the color of signal 20 at the point where it may be observed when sighting the projector; and fourth, to provide a general assembly of parts so constructed and arranged as to facilitate inspection and maintenance.

These objects are attained by the construction 25 illustrated in the accompanying drawings, wherein:

Figure 1 is a side view of the general assembly with certain parts in elevation and others in section.

30 Figure 2 is an end view of the device, partly in elevation and partly in section.

Figures 3, 4 and 5 are top, front and side detail views of the front sight-and-indicator assembly.

35 Figure 6 is a top plan view of the signal control mechanism.

Figure 7 is a detail view of the filter carriages.

In the drawings, 1 indicates the traffic control lamp case of the projector, whose optical system consists of a spot-light lamp 2 located at the 40 focus of a parabolic reflector 3. A spherical mirror 4 is placed in front of the lamp to eliminate direct light from the lamp and to increase the beam intensity. Reflector 3 is retained in place by suitable front clamps 5 and by the back packing 6 which serves to space the reflector from the back 7 of the case. The bottom of the case has an open slot 8 extending centrally and longitudinally thereof and depending from the outer underside of the case and on opposite sides of the slot are strips 9 and 9' defining a channel for the 45 reception of the main frame 10 of the control mechanism hereinafter fully described. The channel-forming strips 9 and 9' are secured to the case by suitable fasteners 11.

Within the front end of the case is a removable glass-retaining ring assembly consisting of the glass retaining ring 12, glass-seating ring 13, clamping ring 14, glass or lens 15, and packing 16. The glass and packing are releasably confined 5 between the sealing ring and the clamping ring which are secured to the retaining ring by removable fasteners 17. A ball 18 and a compression spring 19 are so mounted and arranged on the top of the case that the ball yieldably engages and interlocks with the top portion of the retaining ring 12, through an opening in the top of the case, and thus tends to hold the retaining ring in place. A more positive ring-holding device or catch is provided for the bottom portion of the 10 retaining ring and consists of a flat spring (20) anchored at one end between the frame 10 and the clamp 21 and having at its free end a button 22 extending upwardly through an opening in the frame 10 and engaging in an opening in the bottom portion of the retaining ring. The glass-retaining ring assembly is removable as a unit from the case by pushing down on the spring button with the thumb to release the catch and then sliding the retaining ring out of the case.

25 The control mechanism consists of a lamp socket assembly, a pistol grip assembly, and a color control assembly, supported on and carried by the main frame 10; the latter being of channel section and detachably fastened to the channel strips 9 and 9', in inverted position therebetween, by four forwardly located short screws 23 and nuts 23' and two rearwardly located longer screws 24 and nuts 24'. The longer screws 24 extend through the pistol grip 25 and, together with the 30 socket stem nut 26, constitute the means whereby the pistol grip assembly is fastened to the channel frame 10.

35 The lamp socket assembly consists of a holder 27 for the lamp socket 28, a stem 29 for supporting the holder, and the socket stem nut 26. The bottom end of the holder seats on a shoulder near the upper end of the stem to which it is rigidly fastened by suitable means, such as a screw 30 and it is formed with an upwardly extending arm 40 27' to which is attached the spherical mirror 4. The stem is mounted on the frame 10 with its lower end disposed through an opening in the frame and screw threaded to receive the nut 26. A bearing-shoulder 31 is formed on the stem, inwardly of the nut-bearing end thereof, for abutment with the top side of the frame.

45 The pistol grip assembly includes the pistol grip or rear handle 25 by means of which the 50 completely assembled device is conveniently 55

gripped and held in one hand when directing the beam. The rear pistol grip handle is located at the rear end of the main frame 10 with its upper end disposed between the depending side flanges 5 10a and 10b of the frame to which it is fastened, as previously explained, by the long screws 24 and nuts 24'. The pistol grip handle is substantially hollow, being recessed to receive and to house the trigger and trigger switch assembly 10 which, as a unit, consists of the plate or frame 32 and the various elements mounted thereupon, such as the trigger 33, trigger frame 34 with contact point 35, trigger frame tensioning spring 36, contact spring 37 with contact point 38, contact 15 stop 39, connecting male type plug 40, insulated leads 41 and 41' from the connecting plug to the contact spring and lamp socket respectively, and a holder 42 for the insulated lead or wire 41'. An opening is provided in the upper end of the pistol 20 grip, forwardly of the trigger housing, to receive the lower end of the socket stem 29, the nut 26 of which seats in a recess 43 in the underside of the pistol grip. When the nut 26 is screwed tightly 25 against the pistol grip the latter is thereby clamped firmly to the frame 10. The stem may be keyed to the pistol grip and thereby prevented from turning relatively to the frame.

The color control assembly includes a narrow, substantially elongated, ball-housing block 44 disposed upon the upper face of the main frame 10 forwardly of the lamp socket assembly but set back from the front end of the frame to provide sufficient space for the retaining ring assembly. On its upper side the block 44 is cut out to provide 30 ball housings 45 and 45' located fore-and-aft respectively of a recess 46 in which is seated for rotation an operating disk 47. Disk 47 is fixed, by nut 48, washer 49, and key 50, to the upper end of a drive shaft 51 which extends through a tubular stem 52 on the underside of the block, which stem is inserted through an opening in the main frame 10 to be received in the central opening or socket in the clamping block 21 to which the ball-housing block 44 is secured by screws 53 and 53' 35 as shown in Figure 1. The foremost screw 53' also extends through an opening in the spring 20 of the front ring catch assembly and then serves to anchor the said spring in place. Suitably fixed to the lower depending portion of the drive shaft 50 51 is the color control handle 54 by means of which the drive shaft and the operating disk are turned about an axis.

Disk 47 is provided with diametrically opposed elongated arcuate slots 55 and 55' Fig. 6 in which 55 are disposed the downwardly bent forward ends of drive rods 56 and 56' respectively. These drive rods have downwardly bent rearward ends inserted in tubular sockets 57 and 57' formed at the free ends of lever arms 58 and 58', the latter being 60 integral parts, respectively, of the color filter carriages 59 and 59'. These carriages, shown in detail in Figure 7, are rotatably supported on the socket stem 29 between the bottom end of the holder 27 and the bearing shoulder 31 of the 65 socket stem. Carriage 59 includes an arm 60 to the upper end of which is attached a red filter 61. Similarly, the carriage 59' includes an arm 60' to the upper end of which is attached a green filter 61'. The normal position of the parts of the 70 color control assembly is such as to produce a white beam. That is, the color filters are disposed on opposite sides of the lamp 2 and out of the direct path of the light from the lamp to the parabolic reflector, with the downwardly bent forward ends of the carriage drive rods at the for-

ward extremities of the disk slots 55 and 55'. The carriages are moved separately and independently of one another and are restored after each operation to their normal position by springs 62 and 62'. Carriage restoring spring 62 is attached at 5 one end to the downwardly bent rearward end of the carriage drive rod 56 and has its other end secured to the spring-anchoring side lug 63 of the ball housing block 44. Similarly, the carriage restoring spring 62' is attached at one end to the downwardly bent end of the carriage drive rod 56' and has its other end secured to the side lug 63' of the ball-housing block. 10

As will be apparent from Figure 6, when the operating disk 47 is rotated in a clockwise direction, the drive rod 56' being against the trailing edge of the slot 55' is moved inwardly to turn the carriage 59' and the green filter 61' to the position indicated in dotted lines; the red filter carriage and its drive rod remaining stationary since the slot 55 moves freely by the forward end of the drive rod 56, due to the latter being normally at the leading edge of the slot. When the disk 47 is rotated in a counterclockwise direction from normal position, the red filter carriage is moved, while the green filter carriage remains stationary. Hence, rotating the handle 90° one way will cause a green filter to be placed between the lamp and the parabolic reflector changing the beam to green. Rotating the handle 90° (from normal) the other way will interpose a red filter and change the signal to red. The color filter carriages in their normal position rest against the carriage stop 64 which is fastened, by screw 30 and also screws 65, to the front side of the holder 27. Positive stops are provided, also, for holding the filter control in the desired position. These consist of four cavities or recesses 66 in the peripheral edge of disk 47 and spaced 90° apart, together with a pair of balls 67 and 67' located within the ball housings 45 and 45' respectively and thrust against the edge of the disk for engaging in the said cavities 66 by the force of their respective springs 68 and 68'. 35

To remove the control assembly as a unit, from the case it is only necessary to remove the screws shown along the channel frame in Figures 1 and 2 and then—holding the rear pistol grip firmly in the right hand and the case in the left arm—push the pistol grip forward until the complete assembly slides out. For inspection of the trigger from 32 and its component parts, subsequent to the removal of the control assembly from the case, the socket stem nut 26 is unscrewed from the stem 29 to release the pistol grip 25 which is then withdrawn carefully from its enclosing position about the trigger assembly so that the leads to the lamp socket may not be broken or damaged. All parts of the trigger assembly are then exposed and readily accessible. 45

The projector is provided with front and rear sights 69 and 69' on the top of the case 1 for sighting the beam. At night, due to reflection by dust particles in the air, the color of signaling used can be readily identified. During the day, the color must be checked by other means and for this purpose the present invention includes a novel sighting arrangement in which the front sight 69 is provided with a clear jewel 70 and angle reflector 71 arranged so that a portion of the main beam is directed toward the operator. To this end, the front sight consists of a substantially short and solid barrel-like body or cylinder having a longitudinally extending flat faced base or mounting plate 72 on one side thereof and 50 55 60 65 70 75

arched in conformity with the cylindrical surface of the case 1, to the top of which it is attached by suitable means, such as screws 73. The sight is disposed adjacent the front or lens-mounting end 5 of the case in the manner illustrated in Figure 1 and is provided at its front end with a vertical sight-post 74 having a circular orifice 75 and a pointed sighting bead 76; the orifice 75 being aligned with the peep hole 75' of the rear sight 10 and the bead 76 being aligned with V-notch 76' thereof. Thus, two types of sight are provided. At its rear end, the sight barrel is recessed to provide a reflector chamber 77 opening rearwardly and axially of the barrel through an orifice 78 15 and downwardly and outwardly of the barrel between spaced flanking lugs 79-79', the latter depending within the case through a substantially rectangular opening in the top thereof. The orifice 78 is closed at its outer end by a transparent member, such as the clear glass jewel 70, fitted to the orifice in the manner disclosed, and the wall 77' of the reflector chamber 77 is inclined toward the jeweled orifice at an angle of 45 degrees with respect to the axis of the sight 20 body.

The inclined chamber wall 77' provides a rest or support for the upper half of the right-angle chromium-plated reflector 71, the latter being fixedly secured to the wall by suitable fastening 25 means, such as a screw 78', and having its lower half angularly disposed between the flanking lugs 79-79' so as to be in the path of and to intercept, a small portion of the light rays reflected parallel to the axis of the case from the 30 parabolic reflector 3. The intercepted rays are doubled-reflected 180 degrees by the reflector 71, so as to illuminate the clear jewel 70 with the same color light as is being transmitted as 35 a signal. One ray is indicated in Figure 1 at R and R' to illustrate the double-reflection whereby positive indication of color signal is obtained. This indication is essential for daytime use especially as the operator must accurately train 40 the projector by use of the sights and as his view is restricted to the sights and the objective, the color signal indication must be positive and visible without change in view. This sighting arrangement has the following advantages: first, it provides the operator with a positive 45 indication that a signal is being transmitted; second, it provides a positive indication of color signal being transmitted; third, it provides the foregoing indications without interfering with the sighting of the projector; and, fourth, it 50 facilitates the transmission of a signal as all doubt regarding color or operation is removed.

Electrical current for operation of the device may be supplied from a storage battery by suitable cable connections between the battery and 55 the device or it may be obtained directly from commercial lighting sources. For the latter purpose a transformer 80 is used which will allow operations from commercial lighting sources of alternating current at frequencies from 25 to 60. The transformer has a long secondary lead 81 and a short primary lead 82, the former being provided with a plug 83 for attachment to the plug 40 of the trigger assembly and the latter having an attachment plug 84 60 for connection with a commercial lighting source. When connected to 115 volts alternating current, commercial frequency, the transformer will operate the lamp at seven volts.

In the operation of the traffic control device, 65 the operator points the projector in the direc-

tion of the selected airplane, which may be either on the ground or in the air, and signals the pilot thereof by closing the trigger switch, the color filters being properly positioned according to whether the given signal is red, green, or clear. The information conveyed by the projected signals is of course dependent upon the meaning of the signals in accordance with a common interpretation thereof. For the purposes of the present invention the meaning of the signals will be understood to be as follows: To pilots in air, red indicates "Stay away"; clear indicates "Landing optional with caution" and green indicates "Land"—To pilots on the ground, red indicates "Remain in place"; clear indicates "Remain in place"; and green indicates "Take off" or "Taxi in".

From the foregoing it will be seen that the invention provides a simple, manually operated and controlled, signal projector for ground use in directing and controlling air traffic into and out of an airdrome. The device is designed for use either during the day or at night.

I claim:

1. A portable signalling device comprising the combination of an opaque housing optically opened at one end, intelligence-communicating means within said housing and operable for communicating intelligence through the optically opened end of the housing to a receiving station, sighting means externally of the housing for lining up the device with the receiving station, and reflector means between the intelligence-communicating means and the sighting means optically active during the operation of the device for displaying at the sighting means a functional characteristic of the intelligence-communicating means whereby the operation of the latter can be observed by the operator while the eye is focused on the sighting means.

2. In a traffic control signal projector, sighting means on the projector for training the projector on an objective and indicating means on the projector for indicating whether or not a signal is being transmitted, said sighting means and said indicating means being arranged and combined in the line of sight to be viewed simultaneously for the performance of both functions while the eye is focused on the sighting means.

3. A traffic control signal light projector including a housing having a source of light and focusing means therein, a sighting device mounted on said housing and having a colorless transparent member, and means for intercepting and reflecting part of the signal light through the transparent member to illuminate the latter with the same color light as is being transmitted as a signal, said transparent member being visible substantially along the axis of the sighting device to be viewed simultaneously with the latter while the eye is focused on the sighting device.

4. A traffic control signal light projector including an opaque casing optically opened at one end, a source of light and light-focusing means within the casing, a sight on the outside of the casing, a colorless transparent member rearwardly of the sight and in substantially the same line of vision as the sight so that the said sight and the said member can be viewed simultaneously whenever the eye is focused on the sight, and reflector means for intercepting a small portion of the rays of light emanating from said source of light and reflecting same to the said member to illuminate the latter.

5. A traffic control projector for transmitting a beam of light for signalling purposes and including an opaque housing optically opened at one end and having an opening in the top thereof, a source of light within the housing, focusing means for directing the light from said source through the opened end of the housing, a front sight on the top of said housing having a chamber in communication with the opening in the top of the housing, the said chamber opening rearwardly of the said sight, and a reflector fixed in the said chamber and depending through the opening in the top of the housing to intercept a portion of the light emanating from said focusing means, said reflector having angularly disposed reflector portions for directing the incident light through the chamber opening at the rear of the sight.
6. A combination front sight and indicator for a traffic control projector comprising a substantially short and solid opaque body having a sighting post on one side thereof and a recess leading outwardly of the opposite side of the body and an axial opening at the inner end of the recess and leading outwardly of one end of the body, a colorless jewel covering the axial opening of the body, and a reflector secured to the said body with a reflector portion thereof disposed within

the recess to illuminate the jewel with light reflected therefrom and a reflector portion extending outwardly of the recess and angularly disposed so that incident light is reflected thereby to the other reflector portion.

7. A combination front sight and indicator for a traffic control projector comprising a relatively short and substantially barrel-like body having a longitudinally extending flat-faced mounting plate on the bottom side thereof and a sighting post extending upwardly from the top side thereof and adjacent the forward end of the body, said body having laterally spaced lugs depending downwardly below the mounting plate adjacent the rear end of the body and a reflector chamber opening downwardly between the said lugs and also outwardly through the said rear end of the body, the forward wall of said chamber being inclined toward the open rear end of the body at an acute angle, a colorless jewel covering the opening in the rear end of the body, and an angle-reflector having a reflector portion disposed within said chamber and against and fixedly secured to the inclined wall thereof and having another reflector portion angularly disposed between the said depending lugs.

WILBUR T. HARDING.
